UNITED STATES PATENT OFFICE

CHARLES H. LANDENBERGER, OF PHILADELPHIA, PENNSYLVANIA.

DESIGN FOR A SHAWL-PATTERN.

Specification forming part of Design No. 5,996, dated July 16, 1872.

Specification describing a Design for a Shawl-Pattern, invented by CHARLES H. LANDENBERGER, of the city and county of Philadelphia, State of Pennsylvania.

Design for a Shawl Pattern.

The figure in the accompanying drawing represents sufficient of a shawl-pattern to illustrate my design, which consists of a stripe, A, upon a plain or ornamental ground, B, the said stripe having at each side a border, a, of the ornamental character represented, and a center composed of squares or diamonds, partly concealed by parallel ribs b, ornamented as shown, and extending throughout the strip.

Irrespective of the colors employed, I claim:

The design for a shawl-pattern, substantially as described, and as illustrated in and by the accompanying drawing.

In testimony whereof I have signed my name to this specification in the presence of two subscribing witnesses.

CHARLES H. LANDENBERGER.

Witnesses:

H. DORNEMANN,
JOHN F. TAGUE.
